UNITED STATES PATENT OFFICE

GEORGE LISS, OF PATERSON, NEW JERSEY

ADVERTISING APPARATUS

Application filed February 14, 1931. Serial No. 515,725.

This invention relates to advertising apparatus and particularly to that class of such apparatus in which frames or, as I term them, "leaves" are swung pivotally so as to expose successively advertising matter carried thereby, after the manner of exposing the printed matter of leaves of a book by turning such leaves. I aim to provide an apparatus of this character which may be manufactured at moderate cost and which will operate efficiently and at the minimum expense of power.

According to my invention, combined with suitable supporting means are a turret revolvable therein and a plurality of spaced leaves pivotally shiftable in the turret around axes arranged around and substantially parallel with the turret axis and each having limited shifting movement therein, whereby effort to shift any leaf to its limit will, if continued after such limit is reached, turn the system as a whole. So that two of the leaves may be made to stand apart from each other, or "open", the leaves at any time at one side of a diametric plane coincident with the turret axis and those at the other side of said plane are normally urged to opposite limits, as by arranging the turret axis tilted or otherwise displaced from the vertical so that gravity is active on the leaves. While the apparatus, so constructed, may be operated by hand, I prefer to drive it automatically, as will hereinafter appear.

In the drawings.

35 Fig. 1 is a section of said means and system coincident with the turret axis;
Fig. 2 is a plan thereof;
Fig. 3 is a side elevation; and
Fig. 4 is a section on line 4—4, Fig. 1,
40 looking in the direction of the arrows.

Let 1 designate a suitable support having an upright spindle 2 fixed therein. On this spindle, and supported as hereinafter stated, is revoluble a turret 3 which comprises a sleeve 3a rotative on the spindle and upper and lower heads 3b and 3c fixed to the sleeve. In the heads at equal distances around and from the turret axis are pivoted the swinging frames or leaves 4, their axes being parallel with said axis. On these leaves the matter

to be displayed may be arranged. Each leaf has a stop 5 which may engage the periphery of head 3c to limit the swinging motion of the leaf in either direction, as where when one leaf of two adjoining leaves is already at one limit and the other is moved to the opposite limit they will stand substantially aligned (Fig. 2). Their tendency to remain in this position, and also of the remaining leaves at each side of a front-to-rear diametric vertical plane to swing back, is here the result of gravity, the whole system being tilted back somewhat (Fig. 3).

The observer may operate the system by hand, thus: One of the front two leaves is swung in the turret from its limit shown to its opposite limit, or till checked by stop 5 engaging head 3c, whereupon continued effort applied to the leaf will turn the turret, that is, the system as a whole. For instance, manipulating the left hand front leaf in Fig. 2 to the right in this way will bring it first to the dotted-line position and then to the shown position of the right-hand leaf, leaving the first of these leaves and the next succeeding one in the new or "open" position of the two front leaves of said figure. To releasably hold the turret after each rotary movement thereof the lower head 3c may have notches 6, equal in number to the leaves, and engageable by a stationary pawl 7 having a rounded top upon which the head slides in rotating, said pawl being supported as will appear.

As illustrated and preferably, however, the system is operated automatically, thus:

8 is an electric motor whose rotary element includes an elongated pinion 9 in mesh with an internal gear 10a of a rotary table or actuator 10 having an upstanding picking stud 10b, the actuator being movable up and down on the spindle subject to the coaction of a spring 11 and a camway 12a of a cam 12 against which another stud 10c of the actuator bears, said cam being pinned to the spindle and hence fixed. (The spring may be interposed between flanged collars 13 loose on the spindle; and between the lower collar and a disk 14 resting on support 1 and between the actuator and the cam there may be

anti-friction bearings 15). Assuming the actuator is rotated in the direction of the arrow in Fig. 2 the camway presents at the right side a sudden rise followed by a gradual depression (Fig. 3). Studs 10b and 10c are so related to each other that when stud 10c encounters the rise stud 10b will occupy a radial plane back of the forward left-hand leaf in Fig. 2 and forward of the next left-hand leaf; the extent of the depression of the cam is such that when stud 10c has reached the terminus of such depression stud 10b will occupy a radial plane forward of the right-hand leaf in that figure; and finally the vertical displacement of the actuator, and hence of stud 10b, is such that when it is up the stud will project into the horizontal plane of movement of the bottoms of the leaves and when it is down the stud will be below such plane. Pawl 7 may, as shown, be carried by cam 12.

The automatic operation is as follows: The system is shown in Fig. 2 in rest position, gravity holding the leaves at each side of a front-to-rear central plane, swung back, and therefore, assisted by pawl 7, holding the system as a whole in said position. Assume the motor to be driving the actuator. Stud 10c has just encountered the rise of the cam, so that the actuator rises and the stud 10b is raised and engages the left-hand forward leaf, thereupon shifting it on its own pivot to the dotted line position in Fig. 2 and then (stop 5 of this leaf being now engaged with the turret) acting through said leaf to turn the turret so that said notch 6 clears the pawl 7 and until the next notch is engaged by this pawl, by which time stud 10c will have reached the terminus of the camway depression, causing depression of the actuator and hence of stud 10b so that the latter clears the mentioned leaf; this will leave this leaf in the position of the right-hand one shown in full and have brought the next succeeding leaf to the position of the left-hand leaf shown. Each time the stud 10c is subjected to the influence of the camway this operation will be repeated, and in this way the leaves will be successively and the system as a whole picked around, coming to a pause between each two actuations and with the front two leaves during such pause standing in the "open" position.

Having thus fully described my invention what I claim is:

1. A display apparatus comprising a rotary system including a revoluble turret and a plurality of spaced leaves pivotally shiftable on the turret around axes arranged around and substantially parallel with the turret axis and each shiftable in the turret in either direction and limited as to such shifting independently of the other leaves and directly by the turret.

2. A display apparatus comprising a rotary

system including a revoluble turret and a plurality of spaced leaves pivotally shiftable on the turret around axes arranged around and substantially parallel with the turret axis and each shiftable in the turret in either direction and limited as to such shifting independently of the other leaves and directly by the turret, and means, successively engageable with the leaves, to shift them successively in the turret and to their limits in one direction and thereby rotate said system.

3. A display apparatus comprising, in combination, a support, a rotary display system rotative on the support and having spaced projecting members arranged around its axis of rotation, a driving mechanism including a rotary actuating device slideable axially of itself on said support into and out of rotary driving engagement with said projections, and means to shift said device into and out of such engagement with said projections.

4. A display apparatus comprising, in combination, a support, a rotary display system rotative on the support and having spaced projecting members arranged around its axis of rotation, a driving mechanism including a rotary actuating device slideable axially of itself on said support into and out of rotary driving engagement with said projections, and cam-including means to shift said device into and out of such engagement with said projections.

5. A display apparatus comprising, in combination, a support, a rotary display system having spaced projecting members arranged around its axis of rotation, a driving mechanism including a rotary actuating device slideable axially of itself back and forth into and out of rotary driving engagement with said projections, and a spring and cam, acting oppositely to each other on said device, for effecting the back and forth sliding thereof.

In testimony whereof I affix my signature.
GEORGE LISS.
